DOUBLE ROLLER PULVERIZER

Filed July 26, 1928

UNITED STATES PATENT OFFICE

HARRY S. DICKINSON, OF MOLINE, ILLINOIS, ASSIGNOR TO THE DUNHAM COMPANY,
OF BEREAL, OHIO, A CORPORATION OF OHIO

DOUBLE ROLLER PULVERIZER

Application filed July 26, 1928. Serial No. 295,423.

This invention relates to double roller pulverizers.

An object of this invention is to provide an automatically adjusting draft transmitting means for distributing the force exerted by the weight carrying frame between the front and rear roller sections to obtain the best results.

Another object is to provide a simple and efficient means for holding the rear roller section in a raised or inoperative position.

These and other objects, as will herein-after appear, are accomplished by this invention which is fully described in the following specification and shown in the accompanying drawings, in which—

Figure 1 is an end elevation of a double roller pulverizer embodying the invention, and showing a part of the roller carrying frame cut away, the rollers being on level ground.

Fig. 2 is a similar view showing the rollers on uneven ground wherein the front roller is lower than the rear;

Fig. 3 is a partial enlarged view of the geared connection between the roller carrying frame and weight carrying frame showing part of the former cut away; and

Fig. 4 is a partial slightly reduced section on the line 4 of Fig. 3.

The embodiment illustrated comprises a double roller pulverizer of the journal type shown in my Letters Patent No. 1,650,891, in which there are two longitudinal shafts 10 and 11 upon which are mounted pulverizing and packing rolls 12 and 13. The shafts 10 and 11 are journaled at their ends in suitable bearings carried by the roller carrying frames 14 of which there are two, one at each end of the pulverizer. Each frame 14 is provided with a slot 15 which is preferably vertically disposed to receive the lower end 16 of a weight carrying frame 17. The two weight carrying frames 17 placed one at each end of the pulverizer are secured together by means of angle irons 18 and 19 which are secured thereto by means of bolts 20. Tongues or other draft connections 21 are in turn secured to the angle irons 18 and 19.

The slot 15 has two sides 22 and 23 which

are preferably arcuate, the radii being preferably struck from a common center. The engaging surfaces 24 and 25 of the lower end of 16 of the weight carrying frame are also made arcuate and are disk-like in form, the diameter of the disk being very slightly less than the difference in length between the radii of the arcuate surfaces 22 and 23.

The rolling surfaces 22 and 24 extend only about half way across the side of the slot 15 and the face of the disk 16 respectively, the remainder being taken up by gear teeth 26 and 27. These teeth are loosely meshed, as is shown in Fig. 3, so that only the vertical pressure exerted by the weight of the gear carrying frame 17 is taken by the teeth, the driving pressure being taken by the rolling surfaces 22 and 24. Thus I have provided two members, one of which transmits draft and the other weight. The back of the disk 25 is loosely in engagement with the rear wall 23 of the slot, so that the gear teeth 26 and 27 are held in mesh.

This geared connection between the weight frame and the roller carrying frame with the gears operating vertically, or with an up and down motion of one frame relative to the other, provides a soil pulverizer in which the draft and weight are transmitted to the rollers in a way to produce the best results. As the front roller rises with respect to the latter when going over a large clod, the point of contact between the rolling surfaces 22 and 24 also rises, thereby automatically applying a greater force to the front roller.

The automatic draft pressure transmitting means previously described places the greater portion of the load on the front shaft since the point of support is nearer the front shaft than it is to the rear shaft. More weight is thus placed on the front axle than on the rear axle so as to better crush the clods and pack the soil. Moreover, the point of draft and support for the weight carrying frame being above the center line of the shaft tends to cause the rear shaft to rise as draft is applied with a corresponding increase in pressure on the front shaft and on the pulverizing elements carried thereby.

This arrangement provides a very simple

and efficient means for flexibly carrying the weight carrying frame 17 upon the roller carrying frame 14. To disengage these frames, the weight carrying frame 17 is 5 rocked forward until the surface 25 clears the upper end of the surface 23 and the frame 17 can then be lifted bodily out of engagement with the frame 14.

If desired, the surfaces 22 and 23 may be 10 made straight so that teeth 26 virtually become part of a straight rack. In either form the effective point of support remains substantially at the same distance from the front and rear shafts 10 and 11 regardless of the 15 angular position of the frames 14.

The frames 14 and 17 are provided with holes 28 and 29, respectively, which are adapted to register as shown in Fig. 2, so that a pin or bolt (not shown) may be passed therethrough to lock the frames in a position in which the rear shaft 11 is raised. The entire weight is then carried by the front rollers.

While I have shown and described but a single embodiment of my invention, it is to be understood that it is capable of many modifications. Changes, therefore, in the construction and arrangement may be made which do not depart from the spirit and scope of the invention as covered by the appended claims.

30 I claim:

1. A soil pulverizer comprising a weight frame and roller carrying frames disposed below the weight carrying frame and rockably mounted thereon, said mounting including 35 rolling surfaces, gear teeth adjacent the rolling surfaces for preventing relative slippage therebetween, and means for maintaining said surfaces substantially in contact.

2. A soil pulverizer comprising a weight frame and roller carrying frames disposed below the weight carrying frame and rockably mounted thereon, said mounting including rolling surfaces, gear teeth adjacent the rolling surfaces for preventing relative slipping 45 page therebetween, and means for maintaining said surfaces substantially in contact, the pitch lines of said gear teeth substantially coinciding with the plane of said rolling surfaces.

50 3. A soil pulverizer comprising a weight frame and roller carrying frames disposed below the weight carrying frame and rockably mounted thereon, the roller carrying frame having a vertical slot, the weight carrying frame having a tongue adapted to fit into said slot, said tongue and slot having interengaging rolling surfaces, and interengaging gear teeth adjacent said surfaces.

4. A soil pulverizer comprising a weight 60 frame and roller carrying frame disposed below the weight carrying frame and rockably mounted thereon, the roller carrying frame having a vertical slot, the weight carrying frame having a tongue adapted to fit into said slot, said tongue and slot having inter-

engaging rolling surfaces, and interengaging gear teeth adjacent said surfaces, the opposite end of said slot being substantially concentric with the rolling surface of the slot.

5. A soil pulverizer comprising a weight 70 frame and roller carrying frames disposed below the weight carrying frame and rockably mounted thereon, the roller carrying frame having a vertical slot, the weight carrying frame having a tongue adapted to fit 75 into said slot, said tongue and slot having interengaging rolling surfaces, and interengaging gear teeth adjacent said surfaces, the opposite end of said slot being substantially concentric with the rolling surface of the slot, 80 said tongue terminating in a disk, the diameter of which is substantially the distance between said end and rolling surface.

6. A soil pulverizer comprising a weight 85 frame and roller carrying frames disposed below the weight carrying frame and rockably mounted thereon, the roller carrying frame having a vertical slot, the weight carrying frame having a tongue adapted to fit into said slot, said tongue and slot having 90 interengaging rolling surfaces, and interengaging gear teeth adjacent said surfaces, said slot extending vertically.

7. A soil pulverizer comprising a weight 95 frame and roller carrying frames disposed below the weight carrying frame and rockably mounted thereon, the roller carrying frame having a vertical slot, the weight carrying frame having a tongue adapted to fit into said slot, said tongue and slot having 100 interengaging rolling surfaces, and interengaging gear teeth adjacent said surfaces, said slot extending vertically, the point of contact of said frames being normally above a line drawn through the centers of the rollers. 105

8. A soil pulverizer comprising a weight frame and roller carrying frames disposed below the weight carrying frame and rockably mounted thereon, said mounting including gear teeth engaging along a substantially vertical line, rolling surfaces limiting the meshing of the gear teeth and means for holding said rolling surfaces in engagement. 110

9. A soil pulverizer comprising a weight frame and roller carrying frames disposed 115 below the weight carrying frame and rockably mounted thereon, said mounting including gear teeth engaging along a substantially vertical line, and means for holding said gear teeth in engagement, said frames having holes adapted to register at a predetermined 120 position of the same whereby a bolt may be inserted to lock the frames in said position.

10. A soil pulverizer comprising a weight frame and roller carrying frames disposed 125 below the weight carrying frame and rockably mounted thereon, the roller carrying frame having a vertical slot, the weight carrying frame having a tongue adapted to fit into said slot, said tongue and slot having 130

interengaging rolling surfaces, and interengaging gear teeth adjacent said surfaces, said slot extending vertically, the point of contact of said frames being normally above a line drawn through the centers of the rollers, said frames having holes through the tongue and through the sides of said slot, said holes being adapted to register in a predetermined position of said frames relative to each other to receive a bolt for locking said frames in said position.

11. A soil pulverizer comprising a weight frame and roller carrying frames disposed below the weight frame and rockably mounted thereon, said mounting including means for transmitting weight primarily from the weight frame to the roller carrying frame and including separate means for transmitting draft from the weight frame to the roller carrying frame, the point of application of the draft between the two frames rising nearly vertically as the front part of the roller carrying frame rises with respect to the rear part thereof.

25 In testimony whereof, I have hereunto set my hand this 13 day of June, 1928.

HARRY S. DICKINSON.
